[57] CLAIM

The ornamental design for a fire combustor, substantially as shown and described.

DESCRIPTION

FIG. 1 is a side view of a fire combustor, showing my new design;

FIG. 2 is a top plan view thereof;

FIG. 3 is a front plan view thereof;

FIG. 4 is a rear plan view thereof; and

FIG. 5 is a bottom plan view thereof.

The electrical cord has been omitted in FIGS. 2—5 for ease of illustration.

FIG. 1

FIG. 2

FIG. 3

FIG. 4

FIG. 5
